UNITED STATES PATENT OFFICE

2,591,438

PORTABLE RADIO RECEIVER

Thomas H. Kinman, Robert G. Hibberd, and Cyril
Hayward, Rugby, England, assignors to General
Electric Company, a corporation of New York

Application April 13, 1948, Serial No. 20,746
In Great Britain April 24, 1947

2 Claims. (Cl. 250—14)

1

This invention relates to radio receivers of small size capable of being carried, thus being available for use at any time and in any position, providing the available signal strength is satisfactory. The primary object of this invention is to provide a portable or pocket size radio receiver with a built-in loop antenna of novel construction.

One of the features of the invention is the provision of a carrying handle for a portable or pocket size radio receiver in which is located a built in loop antenna. An audio reproducing device, such as an earphone, is located in the case which encloses the circuits of the receiver and is connected to those circuits by means of a retractable lead so that the device may be withdrawn from the case for use and readily returned to the case when not in use. The reproducing device is arranged to actuate a switch which controls the operation of the receiver circuits.

The features of our invention which are believed to be novel are set forth with particularity in the appended claims. Our invention, itself, however, both as to its organization and method of operation, together with further objects and advantages thereof, may best be understood by reference to the following description taken in connection with the accompanying drawing in which Fig. 1 is a front elevation view, partly in section, of a pocket type radio receiver suitably embodying our invention; Fig. 2 is a vertical side view, partly in section, of the receiver of Fig. 1; and Fig. 3 is a sectional view of the receiver of Fig. 1 taken along the line 3—3.

Referring to Fig. 1, we have illustrated a pocket type radio receiver constructed in accordance with our invention and which comprises a hollow outer casing 1 which may be formed, for example, of metal and to which is connected a rigid carrying handle 2 forming an upper extension of the casing 1 and incorporating therein a loop type receiving antenna 3. In order that the antenna may pick up radio waves, it is of course necessary for the handle 2 to be formed of a suitable insulating material, preferably of the molded type. As seen in Fig. 2, it is thus preferably in the form of two apertured insulating members 4, 5 adapted to fit together with the apertures in alignment to provide the carrying handle. The handle is thus split into two parts. One or both parts of the handle may contain a slot 6 running around the aperture and adapted to receive the turns of wire constituting the receiving loop antenna 3, the ends of the antenna being brought through suitable bores (not shown) in the handle

2

to extend into the casing 1 containing the receiving apparatus.

Preferably the casing 1 is of flat, rectangular form and made of metal, the handle portion 5 being inserted into the upper end of the casing and secured thereto, for example, by screws (not shown). Also, the cross-section of the portion of the handle to which the casing is connected is approximately the same as that of the casing 10 so that the handle and casing together provide a smooth external surface.

The casing 1 may be divided into two compartments, compartment 7 being remote from the handle and containing the batteries (not shown) 15 necessary for operation of the receiving apparatus, while the receiving apparatus itself is contained in the upper compartment 8 which adjoins the handle. The lower portion 7 of the casing may be hinged, as at 9, to provide ready 20 access to the interior of the casing for attention or replacement of the batteries located therein.

Conveniently, in the neighborhood of the junction between the handle 2 and the casing 1, the 25 handle is provided with recesses 10, 11 (best seen in Fig. 3) located at opposite ends of the longer of the transverse dimensions of the handle. In the recess 10 is located a knob 12 which is connected with the tuning apparatus of the receiver, 30 the knob thus being in a convenient position with regard to the handle for operation by the user for tuning purposes. The recess 11, which may be of substantially the same dimension as that of the recess 10 is adapted to receive an audio 35 frequency reproducing device which is illustrated as a miniature earpiece 13 connected with the output of the receiver. The device 13 is provided with an earplug 14 and an enlarged portion 15 which, when in position in the recess 11, 40 is adapted to engage the actuator 16 of a switch 17 used for connecting the receiver circuits to the battery. In operation, withdrawal or insertion of the earpiece 13 actuates the switch 17 to complete or disconnect the battery circuit, respectively.

A cable 18 comprising twin flexible conductors has one end connected to earpiece 13 and is preferably arranged on a rotatable drum 19 located within the casing 1 and spring biased by a centrally positioned spring 20 so that, when the receiver is not in use, the cable 18 may be wound up on the drum when the earpiece 13 is inserted into its recess 11.

The construction of drum 19 is best seen by 55 reference to Fig. 2 and comprises two parallel

disks spaced apart by a small axial distance and arranged in the compartment 8 adjacent one of the inner faces of the casing 1. One terminal of the cable 18 is connected to a contact ring 21, while the other terminal is connected to the plate 22 of the drum 19. Contact 21 is carried upon an insulating block 23 positioned between the spring 20 and the wound cable 18.

Contact ring 21 and plate 22 are arranged to be engaged, respectively, by spring fingers 24, 25, both of which are carried on a plate 26 formed of insulating material and biased into engagement with ring 21 and contact plate 22 by means of a spring 27. The fingers 24, 25 are connected, respectively, to the output terminals of the receiver circuits (not shown). Spring biased contact plate 26 and fingers 24, 25 form a brake for the spring biased drum 19. The brake may be released by means of a push button 28 which depresses one end of a pivoted lever arm 29, the other end of arm 29 being arranged to engage a U-shaped member 30 connected to plate 26 and raise the plate and finger assembly. When the push button 28 is depressed, spring 20 causes rotation of drum 19 to wind the cable 18 on the drum. The cable may be unwound from the drum by merely drawing outwardly thereon.

One of the advantages of our portable or pocket type radio receiver construction is that it permits the use of an adequate antenna compactly arranged in a convenient carrying handle for the receiver. Another advantage is the arrangement of the earpiece 13 to control the operation of the receiver circuits and the connection of that earpiece to the receiver circuit by means of a cable which is wound upon a spring biased drum so that, when the receiver is not in use, the cable 18 is conveniently stored within the receiver casing.

While we have shown a particular embodiment of our invention, it will of course be understood that we do not wish to be limited thereto since various modifications may be made, and we contemplate by the appended claims to cover any such modifications as fall within the true spirit and scope of our invention.

What we claim as new and desire to secure by Letters Patent of the United States is:

1. In a portable radio receiver comprising radio-chassis and sound-reproducing elements, a casing constructed and arranged to enclose and

support said elements, a carrying handle of insulating material having a generally U-shaped portion adapted to be grasped by the hand and a transverse base portion bridging said U-shaped portion, means securing said base portion rigidly to said casing, means defining a circumferentially-complete channel through said portions, a loop antenna located within said channel, and electrical connections between said antenna and said chassis.

2. In a portable radio receiver comprising radio-chassis and sound-reproducing elements, a substantially rectangular casing constructed and arranged to enclose and support said elements, a rigid carrying handle of insulating material, said handle having a generally U-shaped portion adapted to be grasped by the hand and a transverse base portion bridging said U-shaped portion, attachment means for securing said base portion rigidly to one end of said casing, said base portion having substantially the same boundary dimensions as said end of said casing and being arranged to abut against said end so as to form a smooth continuation of the adjoining walls of said casing, means securing said base portion rigidly to said face, means defining a circumferentially-complete channel through said portions of said handle, and a loop antenna having a plurality of turns disposed in said channel, said antenna being operatively connected to said chassis through said base portion.

THOMAS H. KINMAN.
